UNITED STATES PATENT OFFICE.

RUDOLF F. HLAVATY, OF CHICAGO, ILLINOIS, ASSIGNOR OF ONE-HALF TO JOSEPH KANTA, OF CHICAGO, ILLINOIS.

MECHANISM FOR CONVERTING MOTION.

1,275,248.

Specification of Letters Patent. Patented Aug. 13, 1918.

Application filed May 17, 1917. Serial No. 169,181.

To all whom it may concern:

Be it known that I, RUDOLF F. HLAVATY, a citizen of Bohemia, and a resident of Chicago, in the county of Cook, State of Illinois, have invented certain new and useful Improvements in Mechanisms for Converting Motion, of which the following is a specification.

This invention relates to that type of mechanisms adapted to convert a constant rotary motion into an intermittent rotary motion, and which is adapted more particularly for use in the intermittent film feeding type of motion picture machines.

15 And the present improvement has for its object to provide a structural formation and association of parts whereby the above mentioned conversion is attained in an accurate and effective manner, without any lost motion between the parts, and by which the periods of rest of the driven element of the mechanism can be increased to embrace a large portion of the complete revolution of the same, all as will hereinafter more fully appear.

In the accompanying drawings:

Figure 1, is a side elevation of the present mechanism, the driving shaft being shown in section.

30 Fig. 2, is an end elevation of the same.

Fig. 3, is a plan view of the driving cam wheel or drum, detached.

Fig. 4, is a section of the same on line 4—4, Fig. 3.

35 Fig. 5, is a vertical section showing the parts in that position in which active rotation is being imparted to the intermittent driven pinion or drum.

Similar reference numerals indicate like parts in the several views.

Referring to the drawing, 1 designates the driving shaft, and 2 the driven shaft of the mechanism, journaled in angular relation to each other in suitable bearings of a supporting frame or housing. The said driven shaft 2 being usually associated with the intermittent film feeding sprocket drum of a motion picture machine.

45 3 designates the driving cam wheel or drum, fixed on the driving shaft 1 and formed with a peripheral channel or groove 4 of a V shape having a flat bottom. At one point in the circumference of the wheel 3 said holding channel 4 is gapped and merges 55 into a pair of spirally arranged branch chan-

nels 5, 5, which extend in opposite directions in the perimeter of said wheel and as usual in the present type of mechanisms. In the present construction the said spiral channels have parallel and spaced relation to each other, and are adapted to receive a pair of the radial prongs of the hereinafter described driven wheel of the mechanism that are next adjacent to the perimeter of the driving wheel 3, as said driven wheel receives a partial rotation by a detail construction of the driving wheel as follows:

6 designates a spirally arranged operating ridge located between and separating the branch channels 5, 5 aforesaid, and preferably of a rounded form in cross-section as shown. In a spiral or oblique direction said operating ridge 6 is of a concave form approximately concentric with the axis of the driven wheel heretofore referred to, and owing to such concave form in connection with its oblique arrangement the operating ridge 6 is adapted to have operative contact with the next adjacent pair of radial prongs of the driven wheel during the periods in which said driven wheel is receiving intermittent rotation.

In Figs. 1, 2, 3 and 5 of the drawing the peripheral channel 4 and spiral concave rib 6 of the driving wheel 3 are arranged nearer to one end of the perimeter of the wheel in order that a more compact transverse arrangement of the driven shaft 2 and associated mechanisms may be had. With such formation one end of the ridge 6 and of a branch channel 5 will terminate in the above described nearer side of the wheel 3, while the other end of the ridge 6 and of the other branch channel 5, will terminate in the perimeter of the wheel as shown.

The star wheel or pinion above referred to, comprises a hub 7, preferably of the hexagonal shape shown, and from alternate faces or facets of which extend a plurality of radial cone shape prongs 8, preferably three in number. Each alternate face or facet of said hub extends beyond the base of the adjacent prong 8 and it is adapted for close sliding engagement with the walls of the V shaped channel 4 of the driving wheel 3, to prevent any independent movement of the star wheel during the period in which said holding channel and said faces of the hub are in operative engagement. In the present structure there is clearance between 110

the prongs 7 and the walls of the holding channel 4 and the bearing engagement of the star with said holding channel is wholly by means of the series of three alternate bearing 5 faces or facets of the hub 8, above described.

The angular or V form of the holding channel 4, in connection with the angular or faceted formation of the hub 7, constitutes a material feature of the present improvement, as affording a ready and efficient provision for taking up lost motion between the parts due to wear and the like, and which is attained by an adjustment of the hub 7 and its carrying shaft 2 toward 10 the center of the driving wheel 3 to effect a close and extended contact between the faces of the holding channel 4 and the angular faces of the hub 7 aforesaid.

With the present construction the holding channel 4, during approximately seven-eighths of a complete revolution of the driving wheel 3, is in engagement with the bearing faces or facets of the hub 7 of the star wheel, to hold the same positively 20 against any turning movement. In the present construction as the concave and spirally arranged ridge 6 of the driving wheel enters into engagement with the radial prongs 8 of the driven wheel, said ridge 6 moves between and has operative engagement with adjacent sides of an adjacent pair of the radial prongs 8 of the driven wheel, and during such engagement imparts a rapid semi-revolution to said driven 25 wheel, with an absence of quiver, due to the extended surface contact between the parts provided by the present construction. With a termination of the operative engagement just described a succeeding pair of bearing 30 faces of the hub 7 have holding engagement with the walls of the holding channel 4, for a repetition of the operation above described.

In the above described operation of the parts, the pair of spirally arranged channels 5, 5 provide clearance for the outer ends of the radial prongs 8 of the star wheel in the semi-revolutions of the same.

Having thus fully described my said invention, what I claim as new and desire to secure by Letters Patent is:

1. In an intermittent rotary movement mechanism, the combination of a driving wheel formed with an approximately V-shape peripheral channel ending in a space or gap and with a spirally arranged concave ridge disposed in said gap, and a driven wheel comprising a faceted hub and a plurality of radial prongs, the faceted hub being adapted for bearing engagement in the aforesaid peripheral channel and pairs of the radial prongs having serial straddling operative engagement with the aforesaid spiral ridge, substantially as set forth.
2. In an intermittent rotary movement

mechanism, the combination of a driving wheel formed with an approximately V shape gapped peripheral channel ending in a pair of spiral branch channels extending in opposite directions, and with a spirally arranged concave ridge disposed between said branch channels, and a driven wheel comprising a faceted hub and a plurality of radial prongs, the faceted hub being adapted for bearing engagement in the 75 V shape channel aforesaid and pairs of the radial prongs having serial straddling engagement with the aforesaid spiral ridge, substantially as set forth.

3. In an intermittent rotary movement 80 mechanism, the combination of a driving wheel formed with an approximately V-shape peripheral channel ending in a space or gap and with a spirally arranged concave ridge of a rounded form in cross-section disposed in said gap, and a driven wheel comprising a faceted hub and a plurality of radial prongs having a cone shape, the faceted hub being adapted for bearing engagement in the aforesaid peripheral 85 channel and pairs of the radial prongs having serial straddling operative engagement with the aforesaid spiral ridge, substantially as set forth.

4. In an intermittent rotary movement 90 mechanism, the combination of a driving wheel formed with an approximately V-gapped peripheral channel ending in a pair of spiral branch channels extending in opposite directions, and with a spirally arranged concave ridge of a rounded form in cross-section disposed between said branch channels, and a driven wheel comprising a faceted hub and a plurality of radial prongs having a cone shape, the faceted hub being 95 adapted for bearing engagement in the aforesaid peripheral channel and pairs of the radial prongs having serial straddling operative engagement with the spiral ridge aforesaid, substantially as set forth.

5. In an intermittent rotary movement 100 mechanism, the combination of a driving wheel formed with an approximately V-shape channel ending in a space or gap and with a spirally arranged concave ridge 105 disposed in said gap, and a driven wheel comprising a hub of a hexagonal shape and a plurality of radial prongs, the faceted hub being adapted for bearing engagement in the aforesaid peripheral channel and pairs of the radial prongs adapted for serial straddling engagement with the spiral concave ridge aforesaid, substantially as set forth.

6. In an intermittent rotary movement 110 mechanism, the combination of a driving wheel formed with an approximately V shape peripheral channel ending in a pair of spiral branch channels extending in opposite directions, and with a spirally ar- 115

120

- ranged concave ridge disposed between said branch channels, and a driven wheel comprising a hub of a hexagonal shape and a plurality of radial prongs, the hexagonal hub being adapted for bearing engagement in the V shape channel aforesaid and pairs of the radial prongs having serial straddling operative engagement with the aforesaid spiral ridge, substantially as set forth.
- 10 7. In an intermittent rotary movement mechanism, the combination of a driving wheel formed with an approximately V shape peripheral channel ending in a space or gap and with a spirally arranged concave ridge of a rounded form in cross-section disposed in said gap, and a driven wheel comprising a hub of a hexagonal shape, and a plurality of radial prongs having a cone shape, the hexagonal hub being adapted
- 15 for bearing engagement in the V shaped channel aforesaid and pairs of the radial prongs having serial straddling operative

engagement with the aforesaid spiral ridge substantially as set forth.

8. In an intermittent rotary movement 25 mechanism, the combination of a driving wheel formed with an approximately V shape peripheral channel ending in a pair of spiral branch channels extending in opposite directions, and with a spirally arranged concave ridge of a rounded form in cross-section disposed between said branch 30 passages, and a driven wheel comprising a hub of a hexagonal shape and a plurality of radial prongs having a cone shape, the hexagonal hub being adapted for bearing in the aforesaid V shape channel and with pairs of the radial prongs having serial straddling operative engagement with the aforesaid spiral ridge, substantially as set 35 forth.

Signed at Chicago, Illinois, this 12th day of May, 1917.

RUDOLF F. HLAVATY.
